LAUNDRY DRYER

Edward I. Stern, Hartsdale, N.Y., assignor to International Dryer Corp., Yonkers, N.Y., a corporation of New York

Filed Apr. 15, 1960, Ser. No. 60,216

Term of patent 14 years

(Cl. D49—1)

FIG. 1 is a perspective view of a laundry dryer, showing my new design;

FIG. 2 is a front elevational view of the door thereof, on an enlarged scale; and

FIG. 3 is an enlarged cross-sectional view taken on line 3—3 of FIG. 2.

The dominant features of my design reside in the portions shown in full lines.

I claim:

The ornamental design for a laundry dryer, as shown and described.
